FIG. 4.

UNITED STATES PATENT OFFICE.

FERDINAND SCHORNO, OF PASSAIC, NEW JERSEY.

CHIROGRAPHIC REPRODUCING-MACHINE.

1,159,280.

Specification of Letters Patent.

Patented Nov. 2, 1915.

Application filed May 23, 1914. Serial No. 840,492.

To all whom it may concern:

Be it known that I, FERDINAND SCHORNO, a citizen of the Republic of Switzerland, and a resident of Passaic, in the county of 5 Passaic and State of New Jersey, have invented a new and Improved Chirographic Reproducing-Machine, of which the following is a full, clear, and exact description.

Among the principal objects which the 10 present invention has in view are: To provide a machine for mechanically reproducing an exact copy of signatures or other chirographic productions; to provide individual mechanical records for controlling an 15 apparatus of the character described, to individualize the product thereof; to provide a machine adapted for mechanical writing when operated by individualized and successively-installed records; to provide a machine of the character mentioned with a 20 marking tool, variable by pressure applied thereon, and means for controlling said pressure, mechanically identified with the chirography being reproduced; to provide a machine of the character mentioned, operably 25 controlled by mechanical idiosyncratic records; to provide a machine of the character mentioned, having automatic controls for holding in fixed relation the paper preliminary 30 to imparting thereto the chirography produced by said machine; and to provide means for varying the direction of the operation of the marking implement to simulate 35 the movement of the human hand and wrist.

Drawings.—Figure 1 is a top plan view of a machine constructed and arranged in accordance with the present invention, the top cover of said machine being omitted to show the mechanism normally covered 40 thereby; Fig. 2 is a side elevation of the same, certain of the parts being cut away, where necessary, to show the interior arrangement thereof; Fig. 3 is a fragmentary view with portions of the mechanism omitted. Fig. 4 is a detail view in plan, showing an example of the operation of the line-tracing member.

Description.—As seen in the accompanying drawings, a writing pen is held in a 50 clamp head 11. The head 11 is expandable and contractible, by means of a screw 12, on the barrel or holder 13 of a writing pen 14. The pen employed by me is preferably of the type known as "fountain pens." The 55 clamp head 11 is arranged to fit snugly with-

in the cylindrical end portion 15 of an arm 16. For this purpose, the head 11 is provided with a reduced section 17, which is rigidly mounted on a rocking shaft 18.

The holder 13 is provided with a collar 19, 60 said collar having a spur 20 to extend in service within the slot formed by the opening of the sides of the head 11. In this manner the pen may be always returned to its service position after having been released 65 by and removed from the head 11 for the purpose of filling or repair.

The rocking shaft 18, as best shown in Fig. 2 of the drawings, is extended through the arm 16, and is supported in bearings 21 and 22 therein. At the inner end of said shaft an extension 23 is engaged by a connecting rod 24. The connecting rod 24 is similarly attached to an extension 25, with which a second rocking shaft 26 is furnished. The rocking shaft 26 is mounted in bearings formed in short standards 27 and 28, fixedly mounted on a movable platform 29. Extending in a substantially vertical direction from, and rigidly attached to the shaft 26, is an arm 30, to which is pivotally connected a connecting rod 31. As seen best in Fig. 3 of the drawings, the rod 31 extends horizontally, and is pivotally attached to an arm 32, which corresponds with the 80 arm 30 and is normally disposed parallel thereto. The arm 32 is rigidly connected with a shaft 33, which, as shown best in Fig. 2 of the drawings, is mounted in bearing brackets 34 and 35, rigidly secured to 85 and pendent from a table 36. The above described mounting of the shaft 33 definitely locates the working position of said shaft, and the flexible connection between said shaft 33 and the shaft 26 formed by the rod 90 31, permits the relative swing of the shaft 26 when the platform 29 is moved.

The purpose in the above-described construction is to permit a variation of pressure to be imposed on the pen 14. To this end, the shaft 33 is rocked by a crown cam wheel 37, the upper edge whereof is undulated, as best seen in Fig. 2 of the drawings. Resting on the undulating edge of the wheel 37 is a roller 38 mounted on the free end of a 100 crank arm 39. The crank arm 39 is fixedly attached to the shaft 33 to rock the same in sympathy with the movement imparted by the cam wheel 37 to the free end of said crank arm. The undulations of the edge of 105 110

the wheel 37 are platted to correspond with the pressures upon the pen used in forming the original from which the copies are made. Coincident with the plating of the undulated edge of the cam wheel 37, the undulations on the cam wheels 40 and 41 are also platted in the manner as hereinafter set forth.

The platform 29 is movably mounted on a polished bed plate 42. The supports for the platform are felt pads or plugs 43, which are mounted in cups 44 to rest each under a bearing plate 45. The plate 45 is adjusted by means of a feed screw 46, a lock nut 47 being provided for each of said screws, to hold the same in adjusted position. The screws 46 are particularly useful for truing or leveling the platform 29. Said platform, arm 16, shaft 26, and parts connected therewith, including the pen holder 13, and pen 14, are shifted by levers 48 and 49 when said levers are rocked by the cam wheels 40 and 41. The levers 48 and 49 are both pivoted on the same pivot pin 50. The pivot pin 50 is mounted in a standard 51, shown in Fig. 2 of the drawings as fixedly mounted on the bed plate 42. As shown in Fig. 4 of the drawings, all the movements on the plane parallel to the bed plate 42 of the various levers and the platform 29 connected therewith, are concentric with the pin 50. The shaft 26 and arm 16 are held substantially parallel to the lever 48, or in fixed angular relation thereto, by one arm of the lever 49, which is of the bell-crank type, and a connecting link 52, which is pivotally attached to the free end of the lever 48 by a pin 53, and with the platform 29, by a screw pin 54. The lever 49 is similarly connected by means of a screw pin 55, with the platform 29 at the point adjacent the forward end thereof, or at a point proximate to the working position of the pen 14.

The cam wheel 40 functions through the lever 48 and the link 52 to oscillate the platform 29 and arm 16 connected therewith about the pin 55, to reciprocate the pen 14 in a relatively vertical path. If the platform 29 were not reciprocated lengthwise, the resultant of the operation of the cam wheel 40 and connections therewith, would be a vertical line performed by the pen 14, this line varying in accordance with the height of the letters forming the writing being copied. The wheel 41 functions through the bell crank lever 49 to shift the platform 29 and arm 16 lengthwise, swinging the same about the pin 50. The operation of the wheel 41, if not affected by the operation of the wheel 40, would result in a transverse or longitudinal mark equal to and regulated by the width of the letters forming the writing being copied. By the combined actions of the cam wheels 40 and 41, the platform 29, arm 16 and pen 14, are moved to obtain

the combined result, forming by the pen 14, a letter having the contour or shape of the letter of the original.

The machine herein described and shown is designed principally for use in copying or executing signatures or fac-similes thereof. The necessary lateral feed of the table 29 and parts connected therewith is therefore somewhat limited, but whatever the feed or the travel of the table and pen 14 connected therewith, it is provided for by the shape of the cam wheel 41, the contour of which is arranged to provide for the feed of said platform by permitting one of the springs 56 to draw the power arm of said lever toward a shaft 57. The levers 48 and 49 are provided with pins 58 and 59, respectively, which pins bear upon the undulated edges of the cam wheels 40 and 41, being drawn thereto by the springs 56. The cam wheels 37, 40 and 41 are integrally constructed or rigidly connected. The assembled wheels are fixedly mounted on the shaft 57. The lower end of the shaft 57 has fixedly mounted thereon a worm wheel 60, the teeth whereof engage a worm 61 on a transmission shaft 62. At the end of the shaft 62 is loosely mounted a second worm wheel 63, the teeth whereof engage the thread of a worm 64, which usually completes the transmission mechanism for reducing the speed of the armature shaft 65 of an electric motor 66, which is employed as the motive power in the present machine. The motor 66, shaft 65 and wheel 63 are continuously driven. The wheel 63 is loosely mounted on the shaft 62, and is furnished on one face thereof with a clutch tooth 67. Slidably mounted upon the shaft 62, and connected therewith, is a disk 68, which is furnished with a cam tooth 69, adapted to be engaged by the tooth 67. Normally the disk 68 is held away from the face of the wheel 63 by means of a coil spring 70. Integrally connected with the disk 68 is a second disk 71, which is provided with a pin 72 extending from the face of the disk 71 in a direction opposite to the extension of the tooth 69. The object of the pin 72 is to engage a perforation formed in a disk 73, which disk 73 is held stationary upon a fixed bearing member 74. The disks 68 and 71 are moved in unison lengthwise of the shaft 62 to alternately engage the wheel 63 and the disk 73. When engaged by the wheel 63, the shaft 62, worm 61, worm wheel 60 and parts connected therewith are driven, and when the disk 73 is engaged by the disk 71, said shaft, worm, worm wheel and parts connected therewith are held stationary. These engagements are successive and, as far as the engagement of the disks 71 and 73 is concerned, automatic. The initiation of this operation, or the engagement of the tooth 69 with the tooth 67 is manually effected.

To start the machine, a handle 75 is engaged by the operator, said handle extending above the table 36 and through a slot 76 in a plate 77 mounted on said table. The 5 handle 75 is formed at the end of a vertically-disposed lever 78, which lever is operatively connected with a shaft 79 supported in bearings upon the bottom of the machine and extending to and rigidly connected with a rocking arm 80. The upper 10 end of the rocking arm 80 operatively engages the structure having the disks 68 and 71, and preferably a grooved collar disposed between said disks. To engage the collar, 15 the arm 80 is furnished with a yoke 81, the sides whereof have pins to enter the groove in said collar. The connecting mechanism between the lever 78 and the shaft 79 embodies a short pivot shaft 82, to which said 20 lever is rigidly connected, a link bar 83 and upright arms 84 and 85. It will be seen that by varying the lengths relatively, of the arms 84 and 85, the movement of the disks 68 and 71 may be altered.

25 It will be noticed that a certain amount of lost motion is provided in the operation of the arm 80 and disks 68 and 71, to provide for opening the valve 86 in advance of the engagement of the disk 68 and wheel 63, 30 with the consequent movement of the shaft 57 and cam wheels mounted thereon. The purpose of thus opening the valve 86 in advance of the operation of said cam wheels and the pen 14 operatively connected there- 35 with, is to permit a fan having a casing 87 and a rotor mounted on the shaft 65, to draw air through perforations 88 in a face plate 89, or create a partial rarefaction of the air in a chamber 90 below said plate, the air be- 40 ing drawn thence through a duct 91. The pressure of the air thus imposed on a super- posed sheet or piece of paper, or other medium, holds the same in position during the subsequent movement of the pen 14 there- 45 over. To thus operate the valve 86, the lever 78 is provided with a cam-shaped tongue 92. As seen best in Fig. 1 of the drawings, the normal position of the tongue 92 is that where the end of the tongue rests against 50 the side of the lever 93 provided for operating the valve 86. As seen best in Fig. 3 of the drawings, the arm 85 is extended below the shaft 79, while the arm 84 is extended above the shaft 82. In this manner, there 55 is imparted to the shaft 79 a rotation which carries the disks 68 and 71 toward the wheel 63 when the handle 75 of the lever 78 is moved away from the position indicated by the word "Stop" on the plate 77 toward the 60 positions indicated successively by the words "On" and "Start." In this portion of the movement of the handle 75, to wit, that which proximates said handle with the word "On," the valve 86 is opened to permit 65 the fan to draw the air from the chamber

90. At this time, and until in the further movement of the handle 75, said handle reaches the word "Start," the disk 68 has not engaged the wheel 63, and therefore the pen 14 remains stationary and lifted from 70 the paper or the plate 89.

The operator holds the handle 75 opposite the position "Start" until the tooth 69 on the disk 68 is engaged by the tooth 67 on the wheel 63. The first part of the move- 75 ment now imparted to the shaft 62 carries the pin 72 away from the perforation in the disk 73. The operator now releasing the handle 75, the pin 72 operates to maintain the engagement of the teeth 67 and 69, said 80 pin riding on the face of the stationary disk 73. When, in the course of its travel, the pin 72 registers with said perforation in the disk 73, this pin enters said perforation, being forced therein by the spring 70. The 85 arm 80 and the shafts 79 and 82 are simultaneously rocked back to their normal position as illustrated in Fig. 1 of the drawings, where the handle 75 is arrested opposite the station designated by the word "Stop." 90 Any suitable spring is employed to hold the lever 93 of the valve 86 in engagement with the tongue 92.

Operation.—With a machine thus constructed and arranged, the operation is as 95 follows:—The undulations on the cam wheel 37 provide a surface where the roller 38 on the arm 39 is so disposed that the shaft 18 is rocked to lift the pen 14 from the face plate 89. This permits the introduction un- 100 der the point of the pen, of the paper or medium upon which the signature or facsimile is to be inscribed. This having been done by the operator, he moves the handle 75 on the lever 78 to the position indicated 105 by the word "On." The motor 66, as above explained, is continuously running. Likewise, the fan in the casing 87, and the wheel 63, are continuously operating, and are in nowise dependent upon the movement of the 110 handle 75. The valve 86 is preliminarily opened, and the suction produced by the operation of the fan under the face plate 89 operates to fix in position the paper or medium disposed on said plate. In this 115 position, the disks 68 and 71 are disengaged from the disk 73, or not engaged with the wheel 63. This last engagement is now effected by the further movement of the handle 75 to opposite the station designated by 120 the word "Start." This movement of the handle 75 correspondingly moves the tooth 69 of the disk 68 into the path of the tooth 67 on the continuously-running wheel 63. As explained, the preliminary stage of the 125 rotation of the disks 68 and 71 places the pin 72 in riding position on the stationary disk 73, thereby permitting the operator to release the handle 75, which is held thereafter by said pin 72, until the same is 130

brought into register with the perforation provided therefor in the disk 73.

With the inauguration of the rotation of the shaft 62, the battery of cam wheels 37, 5 40 and 41 is rotated. During this rotation, the undulating edges of said cam wheels operate on the roller 38 and the pins 58 and 59 to rock the shaft 18 and the levers 48 and 49 in correspondence with the shape or contour 10 of the undulating edges. At the initiation of the rotation of the wheel 37, the arm 39 is lifted to lower the point of the pen 14 to rest on the paper held on the plate 89. The undulations provided on the raised edge of 15 the wheel 37, now and throughout the operation, rock the shaft 18 to increase or diminish the pressure on the point of the pen 14 in simulation of the idiosyncrasies of the original writer of the signature or inscription 20 being duplicated. The contour of this edge provides that if the signature has two names or a space between words, where no markings are effected, the pen 14 is lifted from engagement with the paper by the 25 rocking of the shaft 18 in correspondence with the work being performed. Coördinate with the operation of the cam wheel 37, the cam wheel 40 oscillates the pen 14 in a vertical path, and the cam wheel 41 functions 30 to oscillate and move the pen point laterally, and to feed the same longitudinally over the plate 89 and paper held thereon. The result of the correlated operations of the cam wheels 40 and 41 is a tracing having 35 all of the idiosyncrasies of the original copy, while the characteristics or idiosyncrasies of pressure have been imparted thereto by the operation of the cam wheel 37. To assist in operating the shaft 18, the retracting spring 40 94 is provided, being connected to and extending between the platform 29 and the connecting rod 24, as best shown in Fig. 2 of the drawings.

At the completion of the signature, the 45 cam wheel 37 provides for elevating the pen 14 from the paper during the continuation of the operation. It will be understood that the machine provides for a maximum length of signature or inscription, and that therefore the feed of the cam wheel 41 continues, 50 irrespective of the varying length of said signatures, or until the pin 72 falls into the

perforation provided in the disk 73, when the spring 70 shifts the disks 68 and 71 and parts connected therewith to release the 55 shaft 62 and hold the cam wheels against further operation of the pen 14 and holder 13 thereof. The handle 75 and lever 78 being returned to their original positions, the valve 86 is closed. The closing of said valve 60 restores the air pressure in the chamber 90 beneath the plate 89 and the paper disposed thereon, thus permitting the removal of said paper having the mechanically-inscribed signature imparted thereto. 65

Claims:

1. A machine as characterized, comprising a marking pen; a support therefor; a feed table for holding paper in operative relation to said pen; means for relatively 70 shifting said pen and table to impart to said paper a line variable in intensity and conforming to a written character, said means embodying a plurality of cam members corresponding to the characters being formed; 75 and a driving mechanism for said cams, embodying an automatic brake therefor to arrest said cams at the completion of the rotation thereof.

2. A machine as characterized, comprising a marking pen; a support therefor; a feed table for holding paper in operative relation to said pen; means for relatively 80 shifting said pen and table to impart to said paper, a line variable in intensity and 85 conforming to a written character, said means embodying a plurality of cam members corresponding to the character being formed; a driving mechanism for said cams, embodying an automatic brake therefor to 90 arrest said cams at the completion of the rotation thereof; means for fixing in stationary relation to said table, the paper disposed thereon; and means for starting an 95 operation of said driving mechanism, said starting means operating to preliminarily secure said paper on said table.

In testimony whereof I have signed my name to this specification in the presence of two subscribing witnesses.

FERDINAND SCHORNO.
